US00D801348S

(12) **United States Design Patent** (10) Patent No.: **US D801,348 S**
Zhu et al. (45) Date of Patent: **** Oct. 31, 2017**

(54) **DISPLAY SCREEN WITH A GRAPHICAL USER INTERFACE FOR A SOUND ADDED VIDEO MAKING AND SHARING APP**

(71) Applicant: **MUSICAL.LY, INC**, San Francisco, CA (US)

(72) Inventors: **Jun Zhu**, Shanghai (CN); **Luyu Yang**, Shanghai (CN)

(73) Assignee: **MUSICAL.LY, INC**, Palo Alto, CA (US)

(**) Term: **15 Years**

(21) Appl. No.: **29/534,247**

(22) Filed: **Jul. 27, 2015**

(51) LOC (10) Cl. **14-04**

(52) U.S. Cl.

USPC **D14/485**

(57) **CLAIM**

The ornamental design for display screen with a graphical user interface for a sound added video making and sharing app, as shown and described.

DESCRIPTION

The FIGURE is a front view of a display screen with a graphical user interface for a sound added video making and sharing app, showing our new design.

The broken lines illustrate the display screen or portion thereof and form no part of the claimed design. The broken lines illustrate portions of the graphical user interface and form no part of the claimed design.
